UNITED STATES PATENT OFFICE

TOMITARO SANO, OF FRESNO, CALIFORNIA

MATCH SAFE

Application filed April 16, 1929, Serial No. 355,467. Renewed April 7, 1932.

This invention relates to match safes and, among other objects, aims to provide a simple and inexpensive safe adapted to house the tray or inner box of the ordinary cardboard match box in which the matches are sold.

In the drawing:

Fig. 1 is a perspective view of one embodiment of the invention;

10 Fig. 2 is a plan view showing the safe in reverse position; and

Fig. 3 is an end view of the safe.

Referring particularly to the drawing, the preferred embodiment of the invention 15 is there shown as being in the form of a sheet metal casing 10 rectangular in cross section, having side walls 11 and 12 and other walls 13 and 14. Both ends are preferably open. As viewed in Fig. 1, the wall 13 forms the 20 top of the safe but, at times, the wall 14 becomes the top of the casing (see Fig. 2), as will be hereinafter described.

The casing is of such size that the tray or inner box 15 of a conventional cardboard 25 match box may be inserted into and completely housed by the casing.

In order that the matches may be removed either singly or a few at a time, the wall 13 is provided with a cross-shaped opening 30 made by cutting two intersecting slots in the walls. The transverse slot 16 extends from side to side of the casing intermediate its ends while the other slot 17 extends longitudinally of the wall 13 and terminates short of the 35 ends of the casing. The width of the slot 16 is sufficient to permit one or more matches to be passed freely therethrough and the width of the slot 17 is such as to permit a thumb or other finger to be inserted therethrough. When the match-filled box 15 is inserted in either end of the casing, the wall 13 is then used as the top of the safe (Fig. 1). The matches may then be easily removed 40 from the safe through the slot 16 by inserting the thumb and one finger through the slot 17.

When the box is full, the matches usually extend transversely of the box and parallel to each other. (See Fig. 1). However, when 50 the box has been half or nearly emptied, the

matches become disarranged as shown in Fig. 2 and they cannot be removed from the safe very readily. In order that the matches may be removed when disarranged, the wall 14 is provided with a rectangular opening 18 which extends nearly to the sides and ends of the safe, the width of the opening being somewhat less than the length of the matches. The box is then removed from the safe and reversed so that the wall 14 becomes the top. The box is re-inserted with its top adjacent to the wall 14 (see Fig. 2). The matches may then be easily disentangled and removed from the safe through the opening 18.

In order to prevent the box from sliding out of the casing, a spring clip 19 is provided at each end of the casing. These clips may be formed on the ends of metal strip 20 secured intermediate its ends to one side of the casing. The clips normally extend partially over the ends of the box but may be sprung outwardly to remove or insert a box. Feet may be provided on the walls 13 and 14 in the form of pressed-out projections 21 near each corner of said walls to prevent the casing from marring the surface on which it is placed. A portion of or both sides of the casing may be roughened, as indicated at 22, to provide a surface on which to scratch the matches. All corners may be rounded, as shown, to prevent the hands or fingers from being cut.

The safe is particularly adapted for use in cigar stores or the like, where the customers sometimes grab a handful of matches. This is prevented by the narrow slot 16, when the wall 13 is used as the top. When the wall 14 is used as the top only a few matches may be removed at a time, as the opening 18 is of less width than the length of a match and with the matches disarranged some of them would catch beneath the flanges at the opposite sides of the opening.

From the foregoing description, it will be apparent that a match safe has been provided which may be manufactured easily and inexpensively, and which is reversible so that matches may be readily removed therefrom when the box therein is full or nearly empty.

Obviously, the present invention is not re-

stricted to the particular embodiment thereof herein shown and described.

What I claim is:—

1. A match safe comprising, in combination, a sheet metal casing open at the ends and having two side walls and two other walls providing a housing for a cardboard match tray; resilient locking means at the ends of the casing to hold the tray in the casing; one of the other walls having a cross-shaped opening therethrough formed by a narrow transverse slot extending to the side of the casing and a longitudinal slot intersecting the transverse slot and terminating short of the ends of the casing to afford access to the matches; the second other wall having a rectangular opening extending near to the marginal edges of the wall whereby the tray may be turned over to expose the matches therethrough; and pressed-out projections in both of said other walls, providing feet to support the casing with either open side on top.

2. A match safe comprising, in combination, a sheet metal casing rectangular in cross section and open at both ends and adapted to house a match box tray; spring means to hold the tray in the casing; one wall of the casing having a cross-shaped opening therein, said wall being the top of the safe when the tray is filled or nearly filled with matches; the opposite wall of the casing having a rectangular opening therein; said casing being reversed with respect to the tray to permit said opposite wall to be the top of the safe when the tray is partially filled.

In testimony that I claim the foregoing as my own, I have hereto affixed my signature.

TOMITARO SANO.
